WINDSHIELD WIPER PROTECTOR

Ray M. Shenk, 2012 W. Excelsior Ave., Lot 202,
Hopkins, Minn. 55343

Filed Dec. 18, 1972, Ser. No. 315,920

Term of patent 14 years

Int. Cl. D12—16

U.S. Cl. D12—155

FIG. 5

FIG. 6

FIG. 1 is a top plan view of the windshield wiper protector showing my design;

FIG. 2 is a front elevational view of FIG. 1;

FIG. 3 is a rear elevational view of FIG. 1;

FIG. 4 is an enlarged end view of FIG. 1;

FIG. 5 is an enlarged sectional view taken along line 5—5 of FIG. 1; and

FIG. 6 is a fragmentary enlarged side elevational view of FIG. 1.

The windshield wiper protector is an elongated, flexible and air inflated tube. The tube has a size and length to push fit into the windshield wiper recess of an automobile to prevent ice and snow from accumulating in the recess and freezing the windshield wiper arms and blades.

I claim:

The ornamental design for a windshield wiper protector, substantially as shown and described.
